UNITED STATES PATENT OFFICE.

PHILIP FRITZ, OF GRAND RAPIDS, MICHIGAN.

ICE-CREAM CABINET.

Application filed November 21, 1921. Serial No. 516,527.

To all whom it may concern:

Be it known that I, PHILIP FRITZ, a citizen of the United States of America, residing at Grand Rapids, in the county of Kent and State of Michigan, have invented certain new and useful Improvements in Ice-Cream Cabinets; and I do hereby declare the following to be a full, clear, and exact description of the invention, such as will enable others skilled in the art to which it appertains to make and use the same.

This invention relates to an ice cream cabinet for the holding and keeping of ice cream. Cabinets of this kind are used for keeping ice cream in brick form many times, and also in many cases for keeping both brick and bulk ice cream at the same time and refrigerate and keep both kinds cold by use of the same ice. It is a primary object and purpose of the invention to construct a cabinet by means of which the above named ends are attained, and at the same time so construct the cabinet that the brick containing cabinet portion is always sealed against the entrance of ice or water thereinto and held firmly in position by being fastened at both its upper and lower ends against any tendency to floating which may occur after the ice is more or less melted. A further object of the invention is to construct the cabinet so that the ice or similar refrigerating material can be readily placed in the cabinet around the brick container with the brick container fully covered and insured against the entrance of any ice, water or salt therein. A still further object of the invention is to construct the cabinet with a protected metal lining which is covered so as to protect the metal against contact with the salty water on its inner sides or from moisture on its outer sides which have a tendency to corrode and rust the lining from either side so as to destroy the usefulness thereof in comparatively short time, and further to protect this protective material on the inner sides of the lining so that it cannot be scraped off or otherwise removed in the handling of the cabinets as in filling the same with ice and packing the same within the cabinets. These and various other features with constructions for accomplishing the same will appear as understanding of the invention is had from the following description, taken in connection with the accompanying drawings, in which,

Fig. 1 is a longitudinal vertical section taken through a cabinet made in accordance with my invention.

Fig. 2 is a plan of the cabinet, with parts broken away and in section to better show the construction, and

Fig. 3 is a fragmentary enlarged vertical section illustrating the manner of covering the metal lining for protection thereof.

Like reference characters refer to like parts in the different figures of the drawings.

In the construction of the cabinet, an outer casing, which may be of wood is made, comprising a bottom 1 and vertical ends 2 and slides 3, within which suitable insulating material, as 4, which may be cork or equivalent material, is placed between the outer casing and the lining which will be later described. Bars 5 of a width substantially equal to the thickness of the insulating material are placed above the same within the sides and ends of the casing and secured in place, above which narrower bars 6 are located against the sides and ends 2 and 3 of the casing and with their upper sides substantially flush with the upper edges of said sides and ends of the casing. A frame 7 having side and end bars lying over the bars 6 and the upper edges of the sides and ends of the casing is placed around the upper edges of the cabinet casing and permanently secured in position as shown.

The lining for the cabinet is of suitable sheet metal, including a bottom 8 and vertical sides and ends 9 which, at their upper edges are turned outwardly to form lips 10 passing above the bars 5 and covered with finishing strips 11 located inside of the bars 6 and over the bars 5 and secured in place in any desired manner. The cork or other heat insulating material 4 is between and fills the space between the lining and the inner sides of the bottom and vertical walls of the outer casing of the cabinet. The outer sides of the lining, before it is secured in the cabinet, is covered with an asphaltic pitch indicated at 12 and is likewise covered with the same composition, as indicated at 13. This composition covers the lining on both sides completely, is impervious to moisture and completely protects the metal lining from action thereon by moisture, brine and the like. In order to keep the pitch composition from being

scratched or otherwise cut through and taken off on the inner sides, I cover the bottom of the lining on its inner side with a wood covering 14 and the sides and ends 5 with a wood covering 15, relatively thin, nails 16 being passed the covering 15 at the upper edges and through the lining sides and ends 9 into the bars 5. The bottom 14 at its edges is cut away on its upper side to 10 form grooves, indicated at 14^a to receive the lower edge portions of the parts 15, holding them in place at their lower ends and at the same time locking the bottom 14 in place.

Substantially at the middle of the cabinet 15 a cross board 17 is located extending between and over the side bars of the upper frame 7 and being permanently secured thereto by screws 18 or other equivalent fastenings. This member has a central opening 20 19 therethrough which is adapted to be closed by a removable cover 20. On the under side of the member 17 and around the opening 19 therethrough, the material is cut away to make a somewhat larger opening at 25 the lower portion and providing a ledge 21 against which or adjacent which the upper edges of a neck 22 of a brick containing receptacle 23 are adapted to come, the lower end of said receptacle resting on the bottom board 14 and held in position by any suitable rack bars 24 as shown. It is evident that the ice cream brick receptacle 23 has its upper end practically sealed except for entrance through the opening 19 in the 35 fixed member 17.

The cabinet is open at each side of the member 17, which openings are designed to be closed by removable covers 25, each having an opening 26 therethrough which may 40 be closed by a cover therefor, indicated at 27. Below these openings receptacles 28 for holding ice cream in bulk may be placed in the cabinet, one at each side of the central brick holding receptacle 23.

45 In filling the cabinet with ice, the bulk receptacles 28 having removable covers thereon (not shown) in accordance with the usual practice, are placed at each end of the cabinet, the covers 25 being removed 50 and the ice with its mixture of salt placed in the cabinet over and around the bulk receptacles 28 and around the brick receptacle 23, it being evident that the cabinet may be entirely filled with the freezing mixture of ice 55 and salt, after which the covers 25 are replaced together with their auxiliary covers 27. The bulk cream is removed from the receptacles 28 in the usual manner, and whenever a brick or bricks of cream are to 60 be sold, the cover 20 is removed, the bricks taken from receptacle 23. The brick receptacle widens downwardly from the upper neck portion, preferably so that when the cabinet is iced the mixture of ice and salt 65 comes partly over the upper portion of the

receptacle, aiding in the refrigerating action. But no ice or salt can get into the receptacle as its upper end is sealed against its entrance.

It is evident that by shortening the cabinet, one can be made to hold the brick receptacle alone, being held in place and 70 iced in the same manner at each side, the only difference in construction being the smaller size of the cabinet and the elimination of openings 26 and auxiliary covers 27 75 therefor which are not needed when the bulk receptacles 28 are not used.

It is evident that the cabinet described is very practical and efficient in service and 80 is particularly durable in its construction owing to the protection to the metal entering into its construction. The asphaltic pitch coating for the metal lining protects the metal completely from contact with 85 moisture, brine and the like, and the pitch cannot be scratched or otherwise broken or removed owing to its inaccessibility, being covered both on the outside and inside. The brick receptacle is particularly clean and 90 sanitary, and the icing of the cabinet is as easy as with any cabinet for use in holding ice cream. The brick receptacle 23, held at both top and bottom as described, cannot be moved out of place from pressure of the 95 ice against it at any one side more than at another, such as may occur as the ice is packed around the same by use of a packing bar. If not thus firmly held, the brick receptacle is practically sure to be moved 100 out of place. The invention is defined in the appended claims and I consider it to comprehend all modifications in structure coming within the scope of the claims.

I claim:

1. A cabinet having bottom, sides and ends and an open upper end, a member partially covering the upper end of the cabinet and permanently secured thereto, said member having a recess in its under side and an opening therein smaller than the recess, a receptacle having an open upper end located in the cabinet, the upper edges of the receptacle entering said recess and the open upper end of the receptacle being directly 110 under the opening through said member, a movable cover member for completing the closure of the upper end of the cabinet and which is adapted to be moved to permit the entrance of ice into the cabinet and around 115 the receptacle, and means to close the opening in the first permanently secured member.

2. A cabinet having bottom, and vertical sides and ends, a covering member located across the open upper end of the cabinet and permanently secured to said cabinet, said covering member having a recess in its under side and an opening therethrough of less size than the outer dimensions of the recess, a receptacle having an open upper 120

- end located in the cabinet, with the upper edges thereof seated in said recess, two movable cover members for covering the upper end of the cabinet one at each side of the 5 fixed member, said movable cover members being movable to position to open the upper end of the cabinet for the entrance of ice into the cabinet at each side of the receptacle, and means for closing the opening in 10 the fixed covering member.
3. In a cabinet having an open upper side, a covering member extending across the upper side of the cabinet between its ends and permanently secured thereto, leaving 15 open portions at each side, said member having a recess on its under side and an opening therethrough above said recess, a receptacle provided with a neck at its upper end and flaring outwardly to both sides 20 below the neck located in the cabinet between the cover member and the bottom of the cabinet, the upper edge portions of the neck seating in said recess, and additional cover members, one to each side of the fixed 25 cover member for completing the closure of the upper side of the cabinet and movable for the entering of ice into the cabinet and around the receptacle.
4. A cabinet having bottom, ends and 30 sides and an open upper side, a relatively narrow member located across the open upper side of the cabinet and permanently secured at its ends thereto, said member having a recess in its under side and an opening therethrough of smaller size than 35 the outer dimensions of the recess, a receptacle located between the bottom of the cabinet and the said member, its upper edges seating in said recess, movable cover members located one at each side of said member and completing the closure for the upper side of the cabinet, each of said cover members having an opening therethrough, and auxiliary covers for closing the openings in 40 said first member and movable cover 45 members.
5. A cabinet comprising an outer casing having bottom and vertical sides and ends, a metal lining fixed in the cabinet and having its bottom, sides and ends spaced from 50 the bottom, sides and ends of the casing, heat insulating material located between the lining and casing, a protective composition covering the lining on its inner and outer sides, and a covering on the inner sides, ends 55 and bottom of the lining over the protective composition.
6. A cabinet comprising an outer casing having a bottom and vertical sides and ends, a metal lining fixed in the cabinet, a protective composition covering the lining on its inner sides, and a covering over said protective composition permanently secured in 60 the cabinet.

In testimony whereof I affix my signature. 65
PHILIP FRITZ.
